UNITED STATES PATENT OFFICE

CHARLES E. NICHOLSON, OF DETROIT, MICHIGAN

ROLLER SCREEN

Application filed January 24, 1928. Serial No. 249,140.

This invention relates to the class of curtains, shades and screens and pertains particularly to a screen designed primarily for window use.

5 The primary object of the present invention is to provide a window screen adapted to be mounted upon the window sash and adapted to be secured to the lower portion of the frame in such manner that the window sash can be raised or lowered as desired without the necessity of the operator of the window moving or adjusting the screen, the screen automatically adjusting itself to cover the opening made by the raising of the window sash.

10 Another object of this invention is to provide, in a manner as hereinafter set forth, a roll-up window screen operating with the sash of the window to which it is attached so that when the sash is lowered the screen will be completely rolled and arranged beneath a protective covering or shield, carried by the window sash, above the screen. In this manner, with a screen of the character embodying the present invention, when the window sash is closed the view through the window is not obstructed by a screen extending thereover, the screen being rolled beneath a protective shield.

15 Another object of the invention is to provide a roll-up window screen so designed that it may be readily applied to or removed from a window sash without the use of tools.

20 A further object of this invention is to provide a roll-up screen of the above described character, which will be of strong and durable construction easy to install and comparatively inexpensive to manufacture.

25 The invention will be best understood from a consideration of the following detailed description taken in connection with the accompanying drawings forming a part of this specification, with the understanding, however, that the invention is not confined to any strict conformity with the showing of the drawings but may be changed or modified so long as such changes or modifications mark no material departure from the salient features of the invention as expressed in the appended claim.

30 In the drawings:

Figure 1 shows the outside of the lower portion of a window structure equipped with the device embodying the present invention.

Figure 2 is a view partly in section taken upon the line 2—2 of Figure 1.

Figure 3 is a section taken upon the line 3—3 of Figure 1.

Figure 3a is a sectional view taken on a plane extending transversely through the spring actuated roller.

Figure 4 shows a modified structure designed to be readily attached to the window sash or removed therefrom.

Figure 5 is a section through one end of a window sash showing the manner in which the structure of Figure 4 is attached thereto.

Figure 6 is a perspective view of the rear of one end of the modified structure.

Figure 7 is a detailed perspective view of a keeper plate used with the modified structure.

Referring to the drawings in detail wherein like numerals of reference indicate corresponding parts throughout, the numerals 1 and 2 indicate the side members and the sill respectively of a window frame, the lower sash thereof being shown in raised position and indicated by the numeral 3.

The present invention comprises a pair of bracket members 4 each of which comprises the side plate 6 having the laterally projecting foot 7 by means of which the bracket is secured to the outer face of a lower rail of the window sash 3. The plate of the bracket 4 is provided with a square slot 8 to receive the square end 9 of a spring controlled roller 10, the plate portion of the bracket 5 being provided with an aperture (not shown) for the reception of the usual trunnion pin in the other end of the roller. This roller is similar to the well known window shade roller and is supported at its ends in the same manner, spring of the roller being shown at 10a in Figure 3a.

Each of the bracket plates 6 has the forward end thereof formed to provide the tapered tongue 11 and, when the plates 4 are in position, there is mounted between these tongues a roller 12.

Secured to and roller about the spring-controlled roller 10 is a wire screen fabric 13

the lower free edge of which is clamped between the plates 14 and 15 as shown in Figure 2. These plates are, as shown, formed from a single long strip bent along its longitudinal center. The plate 15 constitutes the upper plate and has projecting upwardly therefrom and extending throughout the length thereof, the plate member 16. The screen extends across the outer face of this plate 16, in the manner shown. Inwardly of each end of the plate 15 there is formed a pair of transversely extending loops 17 and 18 through which there extends, longitudinally of the plate 15, a bolt 19. The inner end of each bolt is formed to set up a finger hold 20 and surrounding each bolt, between the loops, is a coil spring 21, one end of which engages the outer loop, or the loop 17, while the other end is secured to the bolt as indicated at 22. As will be readily understood from Fig. 3, the bolt at each side of the screen is designed to engage in appropriate receiving recesses in the adjacent portion of the window frame. It will be readily seen that by drawing the bolt handles 20 toward one another the bolts will disengage from the window frame to permit the raising of the screen while the window sash is in raised position.

30 The inner face of each side frame 1 of the sash is provided with the longitudinally extending angled member or sealing strip 23, one flange of which is secured against the frame to cause the other flange to project from the face thereof against the outer face of the screen fabric at one side edge thereof. When the fabric is drawn down the side edges will bear against the back of this inwardly extending portion of the adjacent angled member as will also the ends of the plate 16 and any space formed between the edge of the fabric and the adjacent frame will be covered to prevent the entrance of insects. The roller 12, over which the fabric is drawn when unrolled from its supporting roller, is spaced just far enough from the inner faces of the inwardly projecting portions of the angled members to permit the screen to pass therebetween, thus acting to hold the screen against these members.

Secured to the outer face of the lower rail of the window sash above the screen roller is a downwardly curving hood 24 which extends across and protects the screen and the rollers. The inner edge of the hood 24 has the flange 25 formed there-along for attaching the hood to the sash. As shown in Figure 2 the hood projects outwardly just far enough to permit it to pass behind the inwardly extending flanges of the angled members 23.

Each end of the hood 24 has secured thereto a body of felt 26 which wipes along the inner face of the adjacent frame member 1 to prevent insects from entering between the ends of the hood and the frame.

In Figures 4, 5, 6 and 7, where is shown a modified form of the structure described in Figures 1, 2 and 3, there is provided a pair of screen roller brackets 27 each of which comprises a plate 28 having a reduced outer end 29 and carried upon an escutcheon plate 30. The plate 30 has a rearwardly projecting centrally positioned lug formed upon the rear face thereof as indicated by the numeral 31 and this lug carries a securing plate 32 which is of greater width and less length than the escutcheon plate 30 as is clearly shown in Fig. 6.

One of the supporting plates 28 is provided with a notch 33 for the reception of one end of the screen roller 34 while the other plate is provided with suitable apertures to receive the trunnion or pin (not shown) upon the other end of the screen-supporting roller. The screen carried upon the roller 34 is indicated by the numeral 35.

Supported by and between the reduced portions 29 of the bracket plates 28 is a roller 36 similar to the roller 12 employed in the preferred form and this roller performs the same function as the roller 12 in the preferred form.

Connected to and supported by the escutcheon plates 30 is a hood 37 the upturned flange portion 38 of which extends across the outer face of the window sash 39 to which the modified structure is attached. The modified structure is also provided with the felt 40 upon the ends of the hood 37 for the purpose described in connection with the preferred form.

In order to place the preferred structure in position upon the window sash, the outer face of the sash at each side and adjacent the lower edge thereof is provided with a mortise 41 over which a keeper plate 42 is secured, this keeper plate being counter-sunk, in the face of the sash, as is clearly shown in Figures 4 and 5. The keeper plate 42 is provided with a keyhole slot, the upper portion of which is relatively large and substantially square in configuration as indicated by the numeral 43 while the lower portion is constructed or relatively narrow as indicated at 44, the upper end of the lower portion of the slot opening into the enlarged upper portion 43. When the keeper plates 42 are in the position shown in Fig. 4, and it is desired to attach the screen to the window sash, the two latch plates 32 are each extended through the large portion 43 of a slot in a plate and then allowed to drop so that the stud 31 passes downwardly into the slot 44 thus positioning the latch plates 32 behind the keeper plate 42. In this manner, the screen roller and brackets are securely attached to the window sash.

The lower portion of the screen structure 45 is the same as the structure shown in Figs. 1, 2 and 3 inclusive and therefore needs no

description with this form. The guide plate or angled member 45 is also like that used in connection with the preferred form.

From the foregoing description it will be readily seen that with a window provided with a screen structure of the above-described character, the window will be screened at all times when the sash is open and when the sash is closed or down the screen will be rolled and stored from sight thus making it possible to keep windows close-screened throughout the year without material damage to the screen. With the structure shown in Figures 4 to 7 inclusive, the screen may be readily attached or removed as desired thus enabling the user to take the screen off at the end of the summer. The keeper plates 42 being mounted in the outer face of the sash, will not interfere with the raising or lowering of the sash when the upper sash of the window frame is lowered and it will therefore be readily seen that the removing and replacing of the modified structure is extremely simple.

Having thus described my invention, what I claim is:—

In a window screen device, a vertical angle bar adapted to be secured to a window frame, a screen roller supporting bracket adapted to be secured to a window sash and projecting forwardly therefrom toward the angle bar, and an idler roller, one end of which is carried by the forward terminal of the bracket over which the screen is trained for urging the screen into contact with the angle bar.

In testimony whereof I affix my signature.
CHARLES E. NICHOLSON.
